UNITED STATES PATENT OFFICE.

GEORGE H. GILMAN, OF BELMONT, MASSACHUSETTS.

DRILLING MACHINE.

Application filed February 3, 1921. Serial No. 442,094.

My invention relates to drilling machines and particularly but not exclusively to those for drilling rock and provided with fluid operated feeding mechanism.

5 My invention will be best understood from the accompanying drawings and following description of a specific embodiment of my invention submitted for illustrative purposes, while its scope will be more particularly pointed out in the appended claims.

In the drawings:-

Figure 1 shows in elevation a breast stopper;

15 Fig. 2 is a longitudinal section of the machine according to Fig. 1 on an enlarged scale and with parts broken away;

Figs. 3, 4 and 5 respectively are sections on the lines 3—3, 4—4 and 5—5 of Fig. 2;

20 Fig. 6 is an elevation of the valve controlling the feed cylinder;

Fig. 7 is a section representing the valve carried by the tool actuator in hole blowing position; and

25 Figs. 8, 9, 10 and 11 represent the positions of the valve carried by the feed cylinder.

The herein submitted embodiment of my invention selected for illustrative purposes in general comprises a feed cylinder which 30 carries in slidable relation thereto a hammer drill which is connected to the piston of the feed cylinder.

Referring to the drawings, I have shown a drill steel 1, the polygonal shank 2 of 35 which is carried in a similarly shaped shank receiving recess in the chuck 3 in order that when the latter rotates the steel will rotate with it. Rearwardly of the steel is mounted a hammer 4 for imparting impact to the 40 steel and carried adjacent the rearward portion of the machine is a rotary engine indicated at 5 which actuates the steel by imparting rotative action to the chuck. The details of the mechanism for actuating the 45 steel are not claimed in this application and will only be described with sufficient particularity to convey an understanding of how they are applied to the invention under consideration. In general, this mechanism 50 is similar to that shown in Patent No. 1,605, 715, granted to me November 2, 1926.

As illustrated the motive fluid supply for the hammer and rotary engine is conducted into the tool actuator through a passage 6, 55 whence it finds its way through the passage 7 into the rear end of the hammer cylin-

der to maintain therein a continuous pressure. Motive fluid from the passage 6 is alternately admitted to the cylinder chamber portions 8 and 9, and exhausted therefrom through the passage 21 to cause the hammer to reciprocate. Herein for operating the rotary engine motive fluid from the rearward continuous pressure chamber is conducted thereto through an intake passage 65 indicated diagrammatically at 10 and exhausted therefrom to the atmosphere through a passage indicated diagrammatically at 11.

The casing for the tool actuator shown by the drawings is built up of sections which are held in assembled relation by the four through-bolt 12, the section 13 of the casing providing a valve block for the valve 14. This valve herein is provided with 70 the operating handle 15 and is supplied with motive fluid, in a manner hereinafter to be described, through a passage 16 in the block, whence it may be conducted through the valve passages 17 and 18 to either the 75 passage 6 leading to the tool actuating instrumentalities or as illustrated by Fig. 7 to the passage 19 in communication with the chuck chamber through the exhaust passage 21 and communicating passage 20. In the 80 normal operation of the machine as indicated by Fig. 1, the port 19 is connected to the atmosphere through an arcuate passage 22 formed in the valve and communicating passage 23 formed in the valve block. 85

If the valve 14 is turned clockwise from the position illustrated by Fig. 1 through an angle corresponding to the width of the port 16, motive fluid supply for the drill bit actuating instrumentalities will be interrupted, while if the valve is turned counterclockwise from the position illustrated in Fig. 1 to that illustrated by Fig. 7, communication between the hammer exhaust passage 21 and the atmosphere will be interrupted and both 100 the exhaust passage and the passage 6 leading to the hammer and rotary engine will be supplied. Under the conditions illustrated by Fig. 7, the drill steel will be actuated by rotation but without impact and the air 105 which passes into the chuck chamber will find its way through the passage 24 of the drill steel and "blow" the hole.

In this connection it is to be noted that the usual rock drill provides for the admission 110 of a small amount of air to the hollow drill steel which mingles with the water supplied,

This air acts to keep the sludge away from the cutting end of the bit and in a measure to free the drill hole of sludge. When the drill hole is to be cleaned an abnormal amount of air is admitted thereto, which serves to forcibly eject the sludge and thoroughly clean the hole. This last operation is known as "hole blowing" and as a result thereof the hole is said to be "blown". In the submitted 10 embodiment the normal supply of air is admitted from the exhaust passage and connection 20 when the hammer is in operation and the water is supplied through the usual water tube 60. As has just been described, the 15 abnormal supply of air for "blowing" the hole is admitted when the valve 17 is in the position illustrated by Fig. 7.

As illustrated the feeding mechanism for moving the actuator and tool with relation to 20 the rock comprises a cylinder member 25 which is relatively stationary with respect to the actuator and to means providing a feed piston and feed piston rod, that is to say, a part fitting the cylinder and extending there- 25 from and having one or more working pressure faces in the cylinder acted upon by the motive fluid. As shown this part has a piston head 26 to which is attached a tubular rod 32 extending from the rear end of the 30 cylinder. On the upper side of the cylinder are shown ways 27 and on the lower portion ways 28. Herein slidably carried on the ways 27 is the cradle 29, the latter being provided with four up-standing ears 30 and portions 31 which engage the ways. The projecting ends of the lower bolts 12 holding the 35 sections of the tool actuator casing in assembled relation are received by perforations in the ears 30. In this manner when the bolts 40 are tightened the cradle and sections of the casing are held in assembled relation.

As illustrated the rearmost end of the tubular rod 32 is provided with a reduced diameter portion 33, which provides a shoulder 45 34. The piston head 26 is carried by the reduced diameter portion and is held in position against the shoulder by the flange 35 of the plug 36 which also serves to close the interior of the tubular piston rod to the forward 50 end of the cylinder.

The piston rod is operatively connected to the hammer drill, and herein for this purpose the rod 32 is provided with a reverse bend to provide a portion the end of which 55 is adjacent the valve block for the tool actuator, this end being provided with a tapered portion 37 which is received by a similarly shaped socket in the union nipple 38 carried by the valve block and held in position by the union nut 39. The bent portion 60 of the rod 32 affords a handle particularly useful in spotting the hole under which conditions the supply to the rear end of the feed cylinder may be throttled to provide a 65 light feed and blow and the application of

the tool to the rock controlled by the operator.

In the present embodiment of the invention the interior of the hollow rod 32 is placed in communication with the rearward 70 end of the feed cylinder by means of the port 40 in order that motive fluid admitted to the rearward end of the feed cylinder may be conducted to the intake 16 of the valve 14.

On the rearward end of the feed cylinder 75 is shown the valve casing 41, in which is mounted the turning plug 42 and to which is connected the air hose 43. The valve is provided with the operating handle 44 and the air admitted through the hose is conducted 80 through a longitudinal passage 45 of the valve and communicating radial passages 46 and 47 for supplying air to the rearward end of the feed cylinder and through a trans- 85 versely removed communicating radial passage 48 for supplying air to the forward end of the feed cylinder.

In the same plane as the passages 46 and 47 the valve casing is shown with oppositely located passages 49 and 50 respectively placing 90 the interior of the casing in communication with the rear end of the cylinder and the atmosphere and in the same plane the valve is provided with the exterior arcuate passage 55. When the valve is turned to place either 95 the passage 46 or 47 in communication with the passage 49 the rear end of the cylinder will be supplied with motive fluid and when turned to place the passage 55 in communication with both passages 49 and 50 the rear 100 end of the cylinder will be exhausted.

In the same plane as the passage 48 the valve casing is shown with passages 51 and 53, the passage 51 placing the interior of the casing in communication with a passage 52 105 formed through one of the ways 28 and opening into the forward end of the cylinder and the passage 53 placing it in communication with the atmosphere. In the same plane the valve has the exterior arcuate groove 54. When the valve is turned to place the passages 48 and 51 in communication motive fluid is admitted to the forward 110 end of the cylinder and when turned to place the passage 54 in communication with both passages 51 and 53 the forward end of the cylinder is exhausted.

The operation of the valve 42 will be best understood from Figs. 8, 9, 10 and 11, in which the sections *a—a* and *b—b* correspond to those taken in the lines *a—a* and *b—b* of Fig. 5. Fig. 8 represents the neutral position. It will be noted in this position the passage 49 leading to the rear end of the cylinder and the passage 51 for supplying 120 air to the forward end of the cylinder are blanked. If the valve is turned clockwise from the position indicated by Fig. 8 to that illustrated by Figs. 9, air is supplied to the rear end of the feed cylinder through the 125 130

passages 46 and 49 and thence through the hollow rod 32 to the tool actuator and the air from the forward end of the cylinder is exhausted to the atmosphere through the 50 passages 52, 51, 54 and 53. Under the conditions illustrated by Fig. 9, the tool is fed towards the work and by manipulation of the valve carried by the actuator, percussion may be imparted to the steel or the hole 10 blown at will.

If the valve is turned from the neutral position illustrated by Fig. 8 counterclockwise to that illustrated by Fig. 10, the rear end of the cylinder is supplied with air 15 through the valve passage 47, while the forward end of the cylinder is supplied with air through the valve passage 48. Under these conditions as the forward side of the feed piston head is of greater effective area 20 than the rearward side, the drill steel will be retracted. If it is desired to retract the drill steel without supplying air to the hammer or if it is desired to increase the retractive effort, the valve may be moved 25 counterclockwise from the position illustrated by Fig. 10 to that illustrated by Fig. 11. Under the conditions illustrated by Fig. 11 the forward end of the feed cylinder is supplied with motive fluid through 30 the valve passage 48 and the rearward end of the cylinder is exhausted by reason of the valve passage 55 establishing communication between the passages 49 and 50.

It will be noted that the hammer can be 35 controlled if desired by the valve carried by the feed cylinder, for example, if the machine is being fed forward with the actuator valve positioned for either actuation of the hammer or for blowing the hole, 40 movement of the feed valve to its neutral position will secure the same result as far as the actuator is concerned as if the actuator valve were closed and further when the valve 42 is in the positions illustrated by 45 Figs. 9 and 10 the supply to the actuator may be throttled without affecting the feed. As illustrated by Figs. 1 and 7, it will be noted that the tool may be actuated by applying thereto both percussion and rotation 50 or rotation alone and contemporaneously with the latter the hole may be blown. It is of advantage when the drill steel binds in the hole to actuate the same and blow the hole to loosen it and at the same time apply 55 a retractive force. The feed valve provides that after the actuator valve has been set to blow the hole and rotate the bit, during the retraction of the machine, the rotation and hole blowing may be continued or interrupted at will without affecting the retraction 60 by moving the feed valve respectively to the positions illustrated by Figs. 10 and 11.

For attaching the machine to a suitable 65 support, for example, a tripod or a mine

column I provide the attachment 56 having a support engaging member 57 and the clips 58 which are adapted to slide along the ways 28 and be clamped to said ways and support engaging portion by means of the 70 bolts 59.

It will be noted that the tool actuator may be readily detached from the cradle and a handle carrying member substituted for the rear head block 60 to enable the actuator 75 to be used as a hand tool.

It will be understood that the words "upper" and "lower" and words of like import as applied to the feed cylinder and drill actuator, and the words "stationary" and "movable" as applied to the feed cylinder and feed piston, are used only in their relative sense to facilitate describing the embodiment of the invention shown in the drawings, and that these words as used in 80 the claims are to be considered in the same sense, and not as limitations to any particular position or mode of manipulation of the machine.

Although I have described one specific 85 embodiment of my invention for purposes of illustration, it is to be understood that within the scope of the invention wide deviations from this embodiment can be made without departing from the spirit of the invention.

Claims:

1. In a drilling machine, a hammer drill 90 for actuating a drilling tool, a stationary feed cylinder carrying means for detachably connecting it to a support at a point intermediate its length, said hammer drill being detachably carried by a cradle sliding on said cylinder, a feed piston in said cylinder, a substantially U-shaped connection 100 between said piston and said hammer drill, one arm of said U-shaped connection entering the rearward end of said cylinder and the end of the other arm thereof being connected to the rearward end portion of said hammer drill, said arms being of such length 105 as to permit said hammer drill to traverse the entire length of said cylinder.

2. In a drilling machine, a feed cylinder 110 carrying on its upper and lower sides oppositely disposed pairs of ways extending lengthwise thereof, means slidably carried by the pair of ways at the lower side of said cylinder for attaching said cylinder intermediate its length to a support, a cradle 115 slidably carried by the pair of ways at the upper side of said cylinder, a hammer drill detachably carried by said cradle, a piston in said cylinder, a tubular piston rod extending from the rearward end of said cylinder and having a return bend connected to the rearward portion of said hammer drill, said piston rod being in fluid communication with said cylinder and hammer 120 drill for conducting motive fluid, and con- 125

- trolling means for said motive fluid for independently varying the drilling speed and feeding force.
3. In a drilling machine, a fluid pressure operated hammer drill formed for carrying a drill steel, a fluid operated feeding device comprising a feed cylinder, said cylinder carrying oppositely disposed ways arranged lengthwise thereof, one of said ways carrying means for connecting said cylinder intermediate its length to a support, a cradle slidably mounted in the other of said ways, means for securing said hammer drill to said cradle, a piston in said feed cylinder, a piston rod extending through the rearward end of said cylinder, said rod comprising a tube having a return bend connected to the rearward portion of said hammer drill, the interior of said rod being in fluid communication with said cylinder, and means comprising the interior of said rod for varying the motive fluid supply to said feed cylinder and hammer drill for varying the drilling speed and feeding force.
4. In a drilling machine having provision for carrying a hollow drill steel, feeding means for said steel comprising a feed cylinder containing a feed piston, an operative mechanical connection between said piston and said steel, said piston and cylinder formed to provide differential working pressure surfaces so disposed that when motive fluid acts upon the larger surface said steel will be retracted relative to the work, conduit means providing a fluid connection between the bore of said steel and said cylinder at the side of said piston having the smaller of the differential pressure surfaces, means for supplying motive fluid to said cylinder for action only on the larger of said surfaces whereby the drill steel may be retracted without blowing the drill hole, and means for supplying motive fluid to said cylinder at both sides of said piston whereby said steel may be retracted while the drill hole is blown.
5. In a drilling machine having provision for carrying a hollow drill steel, a fluid operated drill steel actuator, feeding means for said steel comprising a feed cylinder containing a feed piston, an operative mechanical connection between said piston and said steel, said piston and cylinder formed to provide differential working pressure surfaces so disposed that when motive fluid acts upon the larger surface said steel will be retracted relative to the work, conduit means providing a fluid connection between both the bore of said steel and the intake of said actuator and said cylinder at the side of said piston having the smaller of the differential pressure surfaces, means for supplying motive fluid to said cylinder for action only on the larger of said surfaces whereby the drill steel may be retracted without blowing the drill hole or operation of said actuator, and means for supplying motive fluid to said cylinder at both sides of said piston whereby said steel may be retracted while the drill hole is blown and the actuator is in operation.
6. In a drilling machine, fluid actuated feeding means comprising a feed cylinder, a drill actuator mounted to slide upon and supported by said feed cylinder, a feed piston in said cylinder, and a rearwardly extending piston rod formed of a tube having a reverse bend connected to said actuator at its rearward end portion.
7. In a drilling machine, fluid actuated feeding means comprising a feed cylinder, a fluid operated drill actuator mounted to slide upon and supported by said feed cylinder, a feed piston in said cylinder, a rearwardly extending hollow piston rod having a reverse bend connected to said actuator at its rearward end portion, and means for conducting the motive fluid for one of said fluid operated instrumentalities through said rod.
8. In a drilling machine, fluid actuated feeding means comprising a feed cylinder, a drill actuator mounted to slide upon and supported by said feed cylinder, a feed piston in said cylinder, a hollow feed piston rod having a reverse bend, a valve block carried by said actuator at its rearward end portion, and a mechanical and fluid connection between said rod and said block.
9. In a drilling machine, fluid actuated feeding means comprising a feed cylinder, a drill actuator mounted to slide upon and supported by said feed cylinder, a feed piston in said cylinder, and a rearwardly located U-shaped structure operatively connected at opposite portions to said piston and actuator, said structure permitting said actuator to extend beyond the end of said cylinder at each end of its feeding stroke.
10. In a drilling machine, a feed cylinder having longitudinally disposed ways positioned on opposite sides thereof and integrally carried thereby, a support attachment slidably connected to one of said ways, a drill actuator slidably connected to the other of said ways, a feed piston having a piston rod extending through the rearward end of said cylinder, and an operative connection between said piston rod and the rearward end portion of said actuator.
11. In a drilling machine, a cylinder, ways carried by said cylinder, a cradle slidably supported on said ways, a drill actuator carried by said cradle, a feed piston having a piston rod extending through the rearward end of said cylinder, and an operative connection between said piston rod and the rearward end portion of said actuator.
12. In a drilling machine having provision for carrying a drilling tool, a tool actuator

- ator comprising a casing having a separable member at its rearward end, a cradle with means for detachably connecting it to said casing, a feed cylinder having longitudinally disposed ways for slidably supporting said cradle and having a feed piston and a rearwardly projecting piston rod, said separable member having means for attachment to said rod, whereby said actuator may be readily detached from said cradle and a handle carrying member substituted for said separable member to convert said actuator into a hand tool.
13. In a drilling machine having provision for carrying a drilling tool, a tool actuator comprising a sectional casing, a feed cylinder, a feed piston, means for attaching said piston to one of the sections of said casing, a cradle slidably supported by said cylinder, and common means securing sections of said casing and cradle in assembled relation.
14. A rock drilling machine having, in combination, a drill steel actuator having provision for carrying a forwardly projecting drill steel, feeding means for moving said actuator relative to the work, said feeding means comprising a cylinder and piston, said cylinder slidably supporting said actuator, and a connection between said actuator and piston, said connection comprising a substantially U-shaped structure situated at the rear of said cylinder and actuator and providing a rearwardly extending handle for moving said actuator.
15. A drilling machine having, in combination, a drill steel actuator, fluid feeding means for moving said actuator toward the work, said feeding means comprising a cylinder and piston, said cylinder slidably supporting said actuator, a support for said feeding means, and an operative connection between said actuator and piston, said connection entering the rearward end of said cylinder and providing a handle at the rear of said cylinder and actuator for moving said actuator.
16. A drilling machine having, in combination, a fluid operated drill actuator, a fluid operated telescopic feeding means therefor, said feeding means comprising a cylinder and piston, said cylinder slidably supporting said actuator, a tubular connection between said actuator and piston providing a rearwardly extending handle for moving said actuator, and fluid conduit means for supplying one or the other of said fluid operated instrumentalities by way of said tubular connection.
17. In a rock drill, a feed cylinder having ways on opposite sides thereof below the top, a cradle sliding in said ways, a drill steel actuator having a sectional casing held in assembled relation by side bolts, said cradle having ears through which said side bolts pass, a feed piston in said cylinder, a rod having a return bend connecting the rearward side of said piston to the rearward side of said actuator, said rod having a fluid conduit leading from adjacent its point of connection with said actuator to said cylinder.
18. In a rock drill, a feed cylinder having ways on the sides thereof at its top and bottom, a support connection sliding on the ways at the bottom of said cylinder, a cradle sliding on the ways at the top of said cylinder, a drill steel actuator carried on said cradle, a feed piston in said feed cylinder, and a feed piston rod having a return bend connecting said actuator to the rearward side of said feed piston.
19. In a rock drill, a feed cylinder, ways carried by said feed cylinder, a drill steel actuator slidably mounted on said ways, a feed piston in said cylinder having a piston rod with a return bend connected to said actuator, a valve carried by said feed cylinder, and a conduit in said piston rod controlled by said valve for supplying said actuator.
20. In a fluid operated rock drill, a feed cylinder having a drill steel actuator slidably mounted thereon, a feed piston, a rearwardly extending connection between said actuator and feed piston, and means for throttling the motive fluid supply to said actuator and for simultaneously controlling the fluid supplied to said cylinder for securing a slight feeding force, whereby the application of the drill steel to the work may be controlled manually by said rearwardly extending connection.
21. In a drilling machine, a hammer drill having a hammer piston and hollow drill steel, a cleansing fluid tube extending from the rearward end of said hammer drill through said hammer piston for conducting cleansing fluid for passage through said hollow drill steel, a mounting for said tube permitting said tube to be withdrawn through the rearward end of said hammer drill, a feed cylinder and feed piston, said hammer drill being supported by and slidably mounted on said feed cylinder, a feed piston rod having a portion extending from the rearward end of said feed cylinder and a return portion connected to the rearward end portion of said hammer drill, and said portions being spaced to permit said tube to be withdrawn while the machine is assembled.
22. In a drilling machine, a hammer drill having a hammer piston and hollow drill steel, a cleansing fluid tube extending from the rearward end of said hammer drill through said hammer piston for conducting cleansing fluid for passage through said hollow drill steel, a mounting for said tube permitting said tube to be withdrawn through the rearward end of said hammer drill, a

- feed cylinder and feed piston, means for connecting said feed cylinder to a support and mounting said hammer drill for sliding relatively to said feed cylinder, and a substantially U-shaped piston rod structure operatively connected to said feed piston and hammer drill at the rearward end of said machine, said piston rod structure permitting removal of said tube while said machine is 16 assembled.
23. In a drilling machine, a drilling instrumentality including a hammer drill carrying at its forward end a hollow drill steel and having an axially positioned 15 cleansing fluid tube removable through its rear end, a feeding instrumentality including a feed cylinder on which said hammer drill is supported and slidably mounted with its axis substantially in a plane including the 20 axis of said cylinder, a piston in said cylinder having a piston rod positioned axially of said cylinder, said rod having a lower portion extending from the rearward end of said piston and a connected upper portion 25 spaced from said lower portion and connected to the upper part of said end portion of said hammer drill, and said piston rod being hollow for conducting motive fluid for actuation of one of said instrumentalities 30 and being in fluid communication with said cylinder.
24. In a drilling machine, a feeding motor comprising a stationary feed cylinder and a movable feed piston in said cylinder, a drilling motor comprising a hammer cylinder, a substantially U-shaped piston rod disposed 35 in a vertical plane and having its opposite end portions operatively connected respectively to said feed piston and hammer cylinder, said rod extending through the rear 40 end of said feed cylinder and means independent of said rod for slidably connecting said feed cylinder to said hammer cylinder in sliding non-rotatable side by side relation.
25. In a drilling machine, a feeding motor comprising a stationary feed cylinder and a movable feed piston in said cylinder, a drilling motor comprising a hammer cylinder, a hollow substantially U-shaped piston rod 45 disposed in a vertical plane and having its opposite end portions operatively connected respectively to said feed piston and hammer cylinder, said rod extending through the rear 50 end of said feed cylinder, and means for conducting motive fluid through said hollow rod for actuation of one of said motors, means independent of said rod slidably connecting said feed cylinder to said hammer cylinder in sliding non-rotatable side by side 55 relation.
26. In a drilling machine, a feeding motor comprising a stationary feed cylinder and a movable feed piston in said cylinder, a drilling motor comprising a hammer cylinder, a substantially U-shaped piston rod disposed 60
- in a vertical plane including the axes of both said cylinders and having its opposite end portions operatively connected respectively to said feed piston and hammer cylinder, said rod extending through the rear end of 70 said feed cylinder, and means independent of said rod for slidably connecting said feed cylinder to said hammer cylinder in sliding non-rotatable side by side relation. 75
27. A drilling machine having, in combination, a fluid operated hammer rock drill, fluid operated feeding means for said drill comprising a feed cylinder member and a member providing a feed piston and feed piston rod, one of said members of said feeding means being stationary and the other movable, means independent of the movable member for slidably connecting said drill to the stationary member, a substantially U-shaped structure connected to said drill 80 for causing actuating fluid admitted to said cylinder to feed said drill, said U-shaped structure including said movable member and being positioned at the rear of said machine. 85
28. A drilling machine having, in combination, a fluid operated hammer rock drill fluid operated feeding means for said drill comprising a feed cylinder member and a member providing a feed piston and feed 90 piston rod, one of said members of said feeding means being stationary and the other movable, means independent of the movable member for slidably connecting said drill to the stationary member, and means at the rear of said machine including said movable member for connecting said piston to said drill, said means comprising a part laterally offset from said movable member and operatively connected to said drill. 95
29. A drilling machine having, in combination, a fluid operated hammer rock drill, fluid operated feeding means for said drill comprising a feed cylinder and means providing a feed piston and feed piston rod, said rod projecting from the rear end of said cylinder, means independent of said rod for slidably and non-rotatably connecting said drill to said feed cylinder, means including said rod for connecting said piston to said hammer drill, said means including a part operatively connected to said rod and drill, the forward end of said part being in laterally offset relation to said rod to permit said end to move over the side of said cylinder. 100
30. A drilling machine having, in combination, a fluid operated hammer rock drill, fluid operated feeding means for said drill comprising a feed cylinder and means providing a feed piston and feed piston rod, said rod projecting from the rear end of said cylinder, means independent of said rod for slidably and non-rotatably connecting said drill to said feed cylinder, means in- 105

cluding said rod for connecting said piston to said hammer drill, said means including a part operatively connected to said rod and drill, the forward end of said part being in laterally offset relation to said rod to permit said end to move over the side of said cylinder, and means including a fluid conducting conduit in said rod for supplying motive fluid to one of said fluid operated instrumentalities.

31. A drilling machine having, in combination, a fluid operated hammer rock drill, fluid operated feeding means for said drill comprising a feed cylinder and means providing a feed piston and feed piston rod, said rod projecting from the rear end of said cylinder, means independent of said

rod for slidably and non-rotatably connecting said drill to said feed cylinder, means including said rod for connecting said piston to said hammer drill, said means including a part operatively connected to said rod and to said drill, the connection to said drill being at that side thereof which is opposite said cylinder, an axially positioned cleansing fluid tube in said drill removable through the rear end thereof, said part being so formed and disposed as to permit removal of said tube while said part is connected to said drill.

In testimony whereof, I have signed my name to this specification.

GEORGE H. GILMAN.

George H. Gilman

cluding said rod for connecting said piston to said hammer drill, said means including a part operatively connected to said rod and drill, the forward end of said part being in laterally offset relation to said rod to permit said end to move over the side of said cylinder, and means including a fluid conducting conduit in said rod for supplying motive fluid to one of said fluid operated instruments.

31. A drilling machine having, in combination, a fluid operated hammer rock drill, fluid operated feeding means for said drill comprising a feed cylinder and means providing a feed piston and feed piston rod, said rod projecting from the rear end of said cylinder, means independent of said

rod for slidably and non-rotatably connecting said drill to said feed cylinder, means including said rod for connecting said piston to said hammer drill, said means including a part operatively connected to said rod and to said drill, the connection to said drill being at that side thereof which is opposite said cylinder, an axially positioned cleansing fluid tube in said drill removable through the rear end thereof, said part being so formed and disposed as to permit removal of said tube while said part is connected to said drill.

In testimony whereof, I have signed my name to this specification.

GEORGE H. GILMAN.

CERTIFICATE OF CORRECTION.

Patent No. 1,659,138.

Granted February 14, 1928, to

GEORGE H. GILMAN.

It is hereby certified that error appears in the printed specification of the above numbered patent requiring correction as follows: Page 6, line 54, claim 25, after the word "cylinder" insert the words "means independent of said rod for slidably connecting said feed cylinder to said hammer cylinder in sliding non-rotatable side by side relation," and lines 56 to 60, same claim, strike out the comma and words ", means independent of said rod slidably connecting said feed cylinder to said hammer cylinder in sliding non-rotatable side by side relation"; and that the said Letters Patent should be read with these corrections therein that the same may conform to the record of the case in the Patent Office.

Signed and sealed this 3rd day of April, A. D. 1928.

Seal.

M. J. Moore,
Acting Commissioner of Patents.
